United States Patent Office.

JULIUS JACOB, OF NEW YORK, N. Y.

Letters Patent No. 70,220, dated October 29, 1867.

IMPROVEMENT IN UMBRELLAS.

The Schedule referred to in these Letters Patent and making part of the same

TO ALL WHOM IT MAY CONCERN:

Be it known that I, JULIUS JACOB, of the city and State of New York, have invented, made, and applied to use a certain new and useful Improvement in Umbrellas; and I do hereby declare the following to be a full, clear, and exact description of the said invention, reference being had to the annexed drawing, making part of this specification, wherein—

Figure 1 is a section of an umbrella spread containing my improvements.

Figure 2 is a section showing the frame in a folded condition.

Similar marks of reference denote the same parts.

Umbrellas have heretofore been made to fold for the convenience of travellers, so that such umbrellas may be carried in a valise or carpet-bag.

The nature of my said invention consists in constructing the ribs of umbrellas so that one part slides into the other, so that they can be shortened up for transportation or drawn out for use, in combination with a handle that is made of pieces jointed together so that after the umbrella has been folded the handle can also be folded.

In the drawing, *a* represents the first joint of the handle; *b* is the second, and *c* the third joint, connected together by links, and provided with sliding-sleeve tubes *d* and *e*, that stiffen the joint when the handle is straight. This construction allows the handle to be folded up short, as seen in fig. 2. *i* is the crown of the umbrella to which the ribs are connected. *k* is the stretcher, and *l* the traveller or runner to which the stretchers *k* are jointed. Each rib is made of a wire, *m*, with an eye at one end receiving the wire of the crown *i*, and passing at the other end into the tube *n*, that is slotted on one side, in which a projection on the end of the wire *m* travels so as to connect the parts and allow the rib to be shortened by pressing the tube *n* down over the wire *m*. To the end of this tube *n* the stretcher *k* is jointed by ears, as shown, and I employ a second tube, *o*, into which the tube *n* passes, said tube *o* having a longitudinal slot in one side, in which is a projecting piece from the tube *n*, so that these also are connected, but can be slid together into a small compass, as seen in fig. 2, the ribs closing into about one-third their length when distended. I provide crooks or handles *p* at the ends of the tubes *o*, that enable me to draw the tubes out with facility when the umbrella is to be distended. The umbrella is to be provided with any suitable covering; I prefer the thin vulcanized India rubber. The same is to be attached at the outer ends of the tubes *o* and at the crown *i*. The covering may also be connected near the inner ends of the tubes *o*.

When the umbrella is to be used, the handle is first turned out straight, and stiffened, and then the ribs are extended and the cover stretched by seizing the tubes *o* and handles *p* and drawing them all bodily along the handle. The umbrella is then ready for use in the usual manner. The reverse movement reduces the umbrella to a compact, short condition, as in fig. 2. More than two sliding-tubes *n o* may be employed, if desired.

What I claim, and desire to secure by Letters Patent, is—

The umbrella-ribs formed of the sliding-tubes, as shown, in combination with the folding handle and stretchers, as set forth.

In witness whereof I have hereunto set my signature this ninth day of May, A. D. 1867.

Witnesses:

CHAS. H. SMITH,

GEORGE T. PINCKNEY.

JULIUS JACOB.
